UNITED STATES PATENT OFFICE

SUMU IWAMOTO, OF HIGASHI-KU, OSAKA, JAPAN.

PROCESS OF MAKING CHARCOAL AND APPARATUS THEREFOR.

1,227,148.

Specification of Letters Patent. Patented May 22, 1917.

Application filed August 28, 1915. Serial No. 47,864.

To all whom it may concern:

Be it known that I, SUMU IWAMOTO, citizen of Japan, residing at No. 20 Awajimachi, Itchome, Higashi-Ku, Osaka, Japan, have invented certain new and useful Improvements in the Process of Making Charcoal and Apparatus Therefor; and I do hereby declare the following to be a full, clear, and exact description of the invention, such as will enable others skilled in the art to which it appertains to make and use the same.

This invention relates to the manufacture of charcoal; and it comprises a process wherein wood or the like is carbonized in a suitable kiln or retort, with recovery of by-products, and the carbonized wood is then further and more intensely heated by admitting air into the retort to effect partial combustion of said carbonized wood, the resultant charcoal being most desirably removed from the retort while hot and then quickly cooled. The invention further comprises apparatus for carrying out the process aforesaid.

Heretofore charcoal has been produced by either of two principal methods. According to one of these, wood is charred by direct contact with flame and hot combustion gases, part of the wood being burned to furnish the heat required for conversion of the rest into charcoal. As the method is practised in Japan, the treating kiln has no separate combustion chamber, but is provided with what may be termed a ventilation hole or flue, known in Japan as "daishi-ana", which, in conjunction with dampered hot air flues, permits admission of preheated air into the kiln when the wood has been sufficiently carbonized, whereby the carbonized wood is given a final intense heating to a red heat. This intense heating renders the charcoal hard and dense; and although this method has the disadvantage that the valuable by-products go to waste, nevertheless the superior character of the charcoal produced thereby is well recognized.

According to the second or by-product method, the wood to be charred is heated in closed retorts out of contact with air, combustion gases, etc., and the volatile products distilled off from the wood, such as acetic acid and wood alcohol, are recovered in well-known ways. As heretofore practised, however, this method has produced an inferior grade of charcoal which is so brittle and

porous as to have comparatively little value as a fuel.

The primary object of the present invention is to attain the desirable results of both methods referred to while avoiding the drawbacks to which both are subject; in other words, to recover the by-products of wood distillation, and also to produce a high grade charcoal of the quality peculiar to the Japanese method described.

Briefly described, the new method consists in first distilling wood with recovery of the valuable volatile matters driven off, and then hardening and densifying the residual char by an intense final heating effected by combustion of a part of the char itself. To this end a novel type of apparatus is employed, comprising a kiln or retort in which the wood is placed and which is arranged to be indirectly heated by means of flues located in the kiln walls and adapted to receive flame and hot combustion gases from a suitable combustion chamber. The kiln is also provided with a ventilation hole or "daishi-ana" and dampered air-admission pipes connecting with the flues aforesaid, whereby, after the distillation proper has proceeded far enough, preheated air may be introduced into the kiln to effect partial combustion of the charred wood and the desired final heating up of the product.

The invention will be more fully understood by reference to the accompanying drawings, in which:

Figure 1 is a front view of a kiln in which the process may be carried out, the view being partly in section on the line *c-d* of Fig. 3;

Fig. 2 is a plan view of Fig. 1;

Fig. 3 is a horizontal section on the line *e-f-a-b* of Fig. 1;

Fig. 4 is a vertical section on the line *g-h* of Fig. 1; and

Fig. 5 is a vertical section on the line *i-j* of Fig. 1.

Referring to the drawings, 1 designates generally a kiln constructed of refractory material such as stone for example. In the present example, the kiln is shown as comprising a pair of retort chambers in a unitary construction. At the front are provided doors 2 through which charcoal materials, such as wood, can be charged into the retort chambers. Vapor pipes or conduits 3 are adapted to convey products of distillation from the retort chamber and to con-

duct the same to a place of recovery. Leading from the lower part of each retort chamber at the rear and passing upwardly in the rear wall is the ventilation hole or passage known in Japan as the "daishi-ana." This ventilation passage is extended upwardly through conduit 5 which intersects the vapor pipe 3 as shown and extends therebeyond to any convenient point of discharge. 10 The vapor pipe 3 is provided with dampers 6 and 7 on opposite sides of the ventilation passage 5; while the latter is provided with a damper 8 above the point of intersection. On both sides and in the middle of the kiln 15 are located combustion chambers 9, 10 and 11 which heat the retorts. These chambers are located slightly below the level of the retort floors and are provided with doors 9', 10', 11' and 9'', 10'', (not shown) and 20 11'' for fuel-feeding and draft purposes. Communicating with the combustion chambers are flues 12, 13 and 14 which extend horizontally from the chambers toward the back wall of the kiln. The side flues 13 and 25 14 lead to rear flues 15' and 15, respectively; while the center flue 12 branches off to right and left into rear flues of which only one, flue 16, is here shown. The four flues 15, 15', 16 and the flue on the other side corresponding to 16'' curve upwardly into flues 30 17, 17', 18 and 18', respectively. Flues 17 and 17' lead into flues 19 and 19', respectively, which are located in the upper part of the side walls above flues 13 and 14; 35 while flues 18 and 18' unite in flue 20 which lies above the lower middle flue 12. Flues 19, 19' and 20 lead from the rear of the kiln forwardly into chimneys or stacks 23, 22 and 21 respectively, dampers 23', 40 22' and 21' being provided for the several chimneys as shown. The front ends of flues 19, 19' and 20 are connected to the retort chambers proper by means of pipes 24, 25, 26 and 27, as shown. 45 In the present example, the flue system below the retort chambers may comprise flues 28 and 28' leading from the central combustion chamber 9 toward the front of the kiln, and then passing rearwardly in 50 the form of several parallel flues to the flues 16 and 16'. Similarly flue 29 curves forwardly from combustion chamber 10 and then branches into flue 15 at the rear. A similar arrangement (not shown) is provided for combustion chamber 11. 55 In carrying out the new method with the described apparatus, the retort chambers are first charged with wood or similar materials through the doors 2 which are then 60 closed tightly. The chimney dampers 21', 22' and 23' being closed, and hot air dampers 24', 25', 26' and 27' being open, fires are started in the combustion chambers 9, 10 and 11. The flames and hot combustion 65 gases pass rearwardly through flues 12, 13

and 14 and also forwardly through flues 28, 28', 29, etc., and from the latter rearwardly underneath the retort chambers, the combined streams of flame and gases then passing upwardly through the flues at the rear, 70 thence forwardly through the flues in the upper side walls of the retort chambers to the pipes 24, 25, 26 and 27, which convey the substantially inert combustion gases into the retort chambers proper. These gases 75 being incombustible, raise the temperature within the retorts quickly and intensely without any flaming. As soon as the temperature of the materials in the retorts reaches the point where decomposition is 80 about to begin, the dampers 24', 25', 26', and 27' are closed and the chimney dampers 21', 22' and 23' are opened. The hot combustion gases cannot enter the retorts under these conditions, and said retorts are 85 now heated indirectly by conduction through the retort walls. The valuable volatile products of distillation are led off from the retorts through the vapor pipes 3, the dampers 6 and 7 being open and damper 8 being 90 closed.

When the distillation has been continued to a sufficient extent to properly carbonize the materials in the retort chambers, the fires in the combustion chambers 9, 10 and 95 11 are discontinued. Chimney dampers 21', 22' and 23' are now closed; and hot air dampers 24', 25', 26' and 27' are opened; while dampers 6 and 7 are closed and damper 8 is opened. All the doors of the 100 combustion chambers are then opened to admit air which passes through the intensely hot flues and thence into the retort chambers through pipes 24, 25, 26 and 27. The introduction of this highly heated air into the 105 retort chambers produces a partial combustion of the charcoal therein and heats the main bulk thereof to an intense red heat. This hardens and densifies the charcoal as before explained. When the proper degree 110 of hardening is attained, the charcoal is raked out of the kiln while still hot and is buried in ashes so as to cool it quickly. The charcoal resulting from this process, unlike charcoal cooled inside the kiln, is 115 very solid and compact.

While a specific example of the novel process and apparatus has been described for the sake of a clear disclosure, it is to be understood that the invention is not 120 limited to the exact details specified.

What I claim is:

1. The process of making charcoal which comprises carbonizing wood by indirect heating, then further heating the carbonized wood by direct flame, and finally cooling the resultant charcoal. 125
2. The process of making charcoal which comprises carbonizing wood by indirect heating and recovering distillation products, 130

then further heating the carbonized wood by effecting partial combustion thereof, and finally cooling the resultant charcoal.

3. The process of making charcoal which 5 comprises distilling and carbonizing wood in a suitable kiln by indirect heating, then admitting air to the retort to effect combustion of a part of the carbonized wood and to densify the remainder, removing the charcoal from the kiln while still highly heated, and cooling the charcoal quickly.

4. A charcoal kiln comprising a wood-charring retort, means for heating said retort indirectly, means for leading off distillation products from said retort to a place 15 of recovery, means for admitting air to said retort for combustion purposes, and means for leading off combustion products therefrom.

20 5. A charcoal kiln comprising a wood-charring retort, a system of heating flues in a wall of the retort, a combustion chamber arranged to supply heat to such flue system, a conduit for leading off distillation prod-

ucts from said retort, a conduit affording 25 communication between said flue system and the interior of the retort, a conduit for leading off combustion products from the retort, and controlling dampers for the several conduits.

30 6. A charcoal kiln comprising a retort chamber, a duct for leading off distillation products therefrom, a furnace arranged somewhat lower than the floor of the retort chamber, flues leading from said furnace 35 along the side walls and underneath the floor of the retort chamber, a chimney into which said flues may conduct gases, conduit means whereby gases may pass from said flues into the retort chamber, and a ventilation hole or passage through which gases may escape from the retort chamber.

In testimony whereof I hereunto affix my signature in the presence of two witnesses.
